(57) **CLAIM**

The ornamental design for a vehicle mounted projector for advertising, as shown and described.

DESCRIPTION

FIG. 1 is a perspective view of a vehicle mounted projector for advertising showing my new design.

FIG. 2 is a front view of FIG. 1.

FIG. 3 is a rear view of FIG. 1.

FIG. 4 is a right side view of FIG. 1.

FIG. 5 is a left side view of FIG. 1.

FIG. 6 is a top view of FIG. 1.

FIG. 7 is a bottom view of FIG. 1; and,

FIG. 8 is an alternate perspective view of the vehicle mounted projector for advertising shown in an environment of use.

The stippling shown in FIGS. 1-5 and 8 depict a contrast in appearance. The broken lines in FIGS. 1-5 and 8 show portions of the article that do not form part of the claimed design. The broken lines showing a car in FIG. 8 show environment that forms no part of the claimed design.

1 Claim, 8 Drawing Sheets
